FLOW CONTROL VALVE

Richard K. Schrecengost and Joel A. Jannenga, Rockford, Ill., assignors to Greenlee Bros. & Co., Rockford, Ill., a corporation of Illinois

Filed May 31, 1962, Ser. No. 198,939

2 Claims. (Cl. 251—31)

The invention relates to hydraulic flow control valves of the type which may be used in die-casting machines to control the stroke of a hydraulically actuated injection plunger.

The primary object of the present invention is to provide a novel valve of the above character with which the plunger velocity during the injection stroke may be increased in a plurality of precisely controlled and adjustable steps preselected according to the characteristics of the metal being cast and the size and shape of the die cavity being used.

Another object is to provide a unitary flow control valve capable of initially accelerating the plunger at a controlled rate until the metal cylinder has been closed, advancing the plunger into the metal cylinder at a selected constant velocity during the die-filling portion of the injection stroke thereby providing a steady flow of metal into the die, and sharply accelerating the plunger at a preselected final rate so that the plunger closes at high speed.

The invention also resides in the novel construction and mounting of the valve operator whereby the steps in the valve's opening may be adjusted precisely as desired and independently of each other so that the plunger speed and acceleration during each step may be selected exactly to fit the characteristics of the metal and the die.

Other objects and advantages of the invention will become apparent from the following detailed description taken in connection with the accompanying drawings, in which:

FIGURE 1 is a fragmentary elevational view of parts of a die-casting machine embodying the novel features of the present invention with part of the dies and the injection cylinder broken away and shown in section.

FIG. 2 is an enlarged fragmentary end elevation of the control valve assembly.

FIG. 3 is a fragmentary sectional view taken along the line 3—3 in FIG. 2.

FIG. 4 is a diagrammatic view showing the hydraulic circuit of the die-casting machine.

FIG. 5 is a graphic representation of the velocity of the plunger during different portions of the injection stroke.

As shown in the drawings for purposes of illustration, the invention is incorporated in a die-casting machine for injecting molten metal into a mold and holding the metal under pressure as it solidifies, the mold being formed between two die members 10 releasably clamped together in a manner well known in the art. The illustrative machine is of the cold chamber type in which the metal is ladled through a port or well 11 into a bore 12 forming the metal cylinder leading to the die cavity, and a hydraulically actuated plunger 13 slides back and forth in the bore to force the metal into the die cavity.

The plunger 13 is carried by a piston 14 fitted in an injection or shot cylinder 15 axially aligned with the bore 12. To reciprocate the plunger, pressure fluid is delivered alternately to opposite ends of the cylinder 15 from a suitable source, herein an accumulator 17 of conventional construction and operation charged by a hydraulic pump (not shown) and capable of storing a large volume of oil under pressure for delivery to the injection cylinder. Connecting the accumulator to the head end of the cylinder 15 is a passage defined by pipes 18 and 19 (FIG. 1), and interposed in the passage is a valve assembly 20 for

2

selectively opening and closing the passage to operate the plunger.

Herein, the valve assembly 20 includes a generally cylindrical valve head 21 slidable back and forth between an open position and a closed position in a cylindrical chamber 22 formed in a valve body 23, the chamber having an inlet port 24 through one side communicating with the accumulator and an open end 25 forming an outlet port connected to the pipe 19 leading to the injection cylinder. A helically coiled compression spring 27 is confined in the chamber 22 between the closed end 28 thereof and the valve to urge the latter toward the port 25 so that a nozzle end 29 of the valve extends into the port 25 and an annular beveled shoulder 30 encircling the valve seats in the outlet. When the valve is in this closed position (FIG. 3), oil is pumped into the accumulator through an annular chamber 31 around the valve communicating between the inlet port 24 and a conduit 32 leading to the pump.

After a charge of metal has been introduced into the bore, the valve 21 is shifted to the right, as viewed in FIG. 3, to open the ports 24 and 25 and permit oil to flow from the accumulator into the injection cylinder 15 and shoot the plunger 13 into the bore 12 and past the well 11, closing the latter and forcing the metal into the die. The nozzle may be grooved as at 33 (FIG. 3) to obtain a controlled flow through the port 25. To retract the plunger and open the well for the next charge of metal, oil is directed into the rod end of the cylinder 15 through a line 34. The dies are opened for removal of the completed casting and then closed for the next injection stroke of the plunger.

The present invention contemplates a novel valve assembly 20 for opening the passage between the accumulator and the injection cylinder in a plurality of controlled steps whereby the velocity and acceleration of the plunger 13 during different portions of the injection stroke may be preselected according to the characteristics of the metal being cast and the shape and size of the casting. For this purpose, the valve assembly 20 includes a hydraulic valve actuator capable of moving the valve 21 first at a controlled rate of travel into a preselected partially open position thereby steadily increasing the rate of flow of oil into the cylinder 15 and correspondingly accelerating the plunger at a preselected and controlled rate until the well is closed. Then, by leaving the valve in the partially open position, the plunger may be advanced for a short period at a constant rate to provide a steady, predetermined flow of fluid metal into the die cavity to fill the latter at a rate adapted to the type of metal and die. Finally, as the plunger approaches the end of its stroke, the valve may be moved farther toward the open position, again at a preselected rate of travel and again increasing the rate of flow to the injection cylinder to accelerate the plunger. This final acceleration may be at a greatly increased rate to impart a high closing velocity to the plunger. Also, the valve may be stopped short of the fully open position to control the final plunger velocity.

To achieve these ends, the valve actuator includes a reciprocating element, herein a piston 37 slidable in a cylinder 38, connected to the valve to shift the latter toward the open position, and pressure means including flow control means is provided to regulate the rate of travel of the piston 37 and, therefore, to control the rate of acceleration of the plunger 13. A stop member 39 is disposed in a preselected blocking position to block sliding of the piston 37 when the latter has moved the valve to the partially open position, the stop 39 thus determining the velocity of the plunger during the filling portion of the stroke. Selectively operable means is provided to move the stop out of the blocking position when the plunger approaches the end of its stroke so that

the piston 37 moves the valve past the partially open position thereby to increase the flow of oil to the plunger and shoot the latter forward at high speed. Preferably, a first flow controller 40 regulates the initial plunger acceleration and a second flow controller 41, activated when the stop 39 is moved, controls the final rate of travel of the piston 37 and thereby regulates the final acceleration of the plunger. A second stop 42 may be provided to block opening of the valve at a second predetermined point thereby determining the open position and the highest fluid flow during each injection stroke.

Herein, the cylinder 38 is formed in the valve body 23 adjacent the closed end 28 of the chamber 22 and preferably is coaxial with the chamber, and a rod 43 extending through and journaled for endwise sliding in the common wall 44 between the cylinder 38 and the chamber rigidly joins the piston 37 and the valve for sliding back and forth in unison. The spring 27 is coiled around the rod 43 and urges the piston 37 into its normal, retracted position adjacent the wall 44 and against the end of a collar integral with the wall 44 and encircling the rod to provide the bearing for the rod. Seal rings 45 encircling the rod within the bearing prevent oil leakage through the wall.

The pressure means for moving the valve toward the open position at a controlled rate include, in this instance, a conduit 47 for delivering pilot pressure fluid to the cylinder 38 to move the piston 37 away from the end wall, while pressure fluid trapped within the chamber 22 resists movement of the piston away from the wall, the flow controller 40 comprising an adjustable needle valve interposed in a drain line 48 communicating with the chamber through conduit 49 to restrict the flow of trapped fluid from the chamber and thereby retard the movement of the piston 37 and valve 21. By adjusting the needle to increase or decrease the flow through the lines 49 and 48, the rate of travel of the piston during this step and, accordingly, the acceleration of the plunger, are correspondingly increased or decreased. It will be apparent that fluid could be confined within the head end of the cylinder 38 with the same result. In the illustrative embodiment, however, this end of the cylinder communicates with the outlet port 25 through a vent line 50 extending through the rod to maintain a balance of pressure at opposite ends of the piston assembly.

Shown in FIG. 5 is a graphic representation illustrating one combination of steps obtainable with the novel valve assembly. In the graph, the vertical coordinate represents both the velocity of the plunger and the volume of flow into the injection cylinder, the two being directly proportional. The initial acceleration is represented in FIG. 5 by the slope of the line 51.

In this instance, a second hydraulic actuator comprising a piston 52 slidable in a cylinder 53 disposed in end-to-end relation with the cylinder 38 and preferably coaxial therewith is formed in the valve body 23 to provide selectively operable means for moving the stop 39 into and out of its blocking position. As shown in the drawings, the stop may be formed by a rod 54 extending through the partition 55 between the cylinders 38 and 53 and preferably fastened at one end to one of the pistons with the other end terminating adjacent the other piston, the free end thus coacting with the adjacent piston to form the stop 39. Herein, the rod is secured to the piston 52 with the free end spaced a short distance from the piston 37 to abut against the latter and interrupt its movement away from the wall 44 when the valve is in the partially open position.

Normally, the piston 52 is urged against the partition 55 by pilot pressure fluid directed into the head end of the cylinder through a conduit 57. Thus, when the piston 37 abuts against the rod, further opening of the valve 21 is blocked until the rod is moved out of the blocking position. With the valve held in this position, a constant volume flow from the accumulator to the injection cylin-

der is maintained and the plunger is advanced at a constant velocity, as indicated by the line 58 in FIG. 5.

Movement of the rod 54 out of the blocking position is accomplished by delivering oil under pressure to the rod end of the cylinder 53 through a conduit 59 thereby to shift the piston 52 to the right as viewed in FIGS. 3 and 4. The second flow controller 41 activated when the stop 39 is moved out of its blocking position herein comprises a second needle valve interposed in a normally closed drain line 60 which is connected in parallel with the line 48 and is opened when the stop 39 is moved. To provide a rate of plunger acceleration different from the initial rate, the needle 41 may be set to accommodate a greater volume of flow from the chamber 22 than does the needle 40. Accordingly, the piston 37 and valve 21 will move to the right at a faster rate than before thereby completing the filling of the die and compacting of the metal at high speed. When the needle 41 is left completely open, a sharp increase in plunger speed is obtained as indicated at 61 in FIG. 5. A different setting of the needle 41 will effect an increase in acceleration greater than the initial rate yet less than instantaneous, this being indicated in phantom at 62 in the graph.

If the valve 21 is moved to the fully open position, the full capacity of the system will be delivered to the injection cylinder. If, on the other hand, a lower plunger speed than the highest obtainable is called for by the characteristics of the metal and the die, opening of the valve may be limited by interrupting movement of the piston 37 at a second point. In this instance, the stop 42 utilized for this purpose is formed by a rod 63 extending into the cylinder 53 through the rod end thereof and having a free end disposed adjacent and in the path of the piston 52 to abut against the piston after the latter has shifted the stop 39 a predetermined distance away from the piston 37. In this manner, the level of the line 64 (FIG. 5) is determined.

The invention also contemplates constructing and mounting the valve actuator in a novel manner so that each of the steps in the opening of the valve may be adjusted precisely as desired and independently of the other adjustments and, therefore, the plunger velocity during each portion of the injection stroke may be selected exactly to fit the characteristics of the particular metal and the die. To these ends, the piston 52 is adjustable relative to the piston 37 to adjust the stop 39 and vary the stroke of the piston 37 thereby to select the partially open position of the valve 21, and the stop 42 is adjustable toward and away from the piston 52 without disturbing the setting of the stop 39.

For these purposes, the cylinders 38 and 53 are formed in a hollow, open-ended sleeve 65 divided intermediate its ends by a transverse wall forming the partition 55, and the sleeve is telescoped into a cylindrical recess 67 in the valve body so that the inner end of the recess forms the end of the cylinder 38 against which the piston 37 normally abuts. To adjust the stop 39, means is provided to shift the sleeve axially in the recess and maintain a selected position of the sleeve therein thereby to shift the partition and the piston 52 toward and away from the piston 37. In this instance, this means comprises threads 68 around the exterior of the sleeve and in the wall of the recess.

Turning of the sleeve to shift the stop 39 back and forth to adjust the stroke of the piston 37 may be accomplished conveniently by a hand wheel 69 fixed to a hub 70 formed integrally with the outer end of the sleeve. To lock the sleeve in a selected position, a collar 71 is telescoped loosely around the sleeve for abutment with the hub and is releasably secured to the sleeve by a radially extending pin 72 urged by a spring 73 into one of a plurality of bores 74 angularly spaced around the sleeve. A knob 75 is provided to disengage the pin thereby permitting turning of the sleeve relative to the collar. The collar 71 is locked against turning relative to the

valve body by means of an axially extending dowel pin 77 with opposite ends seated in registering bores in the collar and in the body, the pin 77 being urged toward the collar by a compression spring 78 confined in the bore 79 in the body. Thus, as the sleeve is shifted in and out, the spring 78 extends and contracts to press the pin 77 into the collar and, therefore, holds the latter firmly against the hub 70.

As shown in FIG. 3, an indicating finger 80 may be fast on the body 23 to project axially over the collar 71, and the latter may be marked with calibrations to indicate the amount of axial adjustment of the sleeve. When a desired adjustment has been made, the sleeve is locked in place by seating the pin 72 in the registering one of the bores 74 in the sleeve.

The passages 57 and 59 opening into the cylinder 53 on opposite sides of the piston 52 communicate respectively with axially spaced annular chambers 81 and 82 encircling the sleeve. These chambers are made of substantial axial width to maintain communication with conduits 83 and 84 in the valve body in any of the various axial positions of the sleeve relative to the body.

Closing the outer end of the sleeve 65 is a plug 85 telescoped into the sleeve and having an annular flange 87 for abutting against the hub 70 and receiving bolts 88 (FIG. 3) which are threaded into the hub to hold the plug 85 in place. Thus, the inner end of the plug forms the end wall at the head end of the cylinder 53. The stop rod 63 extends axially through the plug and into the cylinder and herein is threaded at 89 in the plug thereby providing means for adjusting the stop 42 toward and away from the piston 52. A hand wheel 90 is keyed to the outer end of the rod 63 to facilitate turning of the latter, and a collar 91 (FIG. 3) is disposed around the rod and in abutment with the wheel 90. This collar is releasably locked to the wheel by a pin 92 which may be disengaged by a knob 93, and a pin 94 locks the collar 91 against turning relative to the hub 70. A finger 95 extends over calibrations on the collar 91 to indicate the amount of adjustment of the stop 42.

With this arrangement, the operator first adjusts the stop 42 by disengaging the pin 92 and then turning the wheel in the appropriate direction until the end of the rod 63 is disposed the desired distance from the piston 52. Then the pin 92 is locked in the collar 91 and the position of the stop 42 is thereby fixed. Then the pin 72 is disengaged and the wheel 69 turned until the desired increment of change in the position of the stop 39 has been made, as indicated by the position of the finger 80 relative to the collar 71. It will be apparent that both the piston 52 and the stop 42 move in unison with the sleeve 65 thereby maintaining the first adjustment. When the pin 72 is locked in the sleeve, the strokes of the pistons 37 and 52 are determined. The number of settings for each stop is limited only by the locking means, in this instance the spacing of the recesses engaged by the pins 72 and 92.

Operation

The novel features of the present invention will be apparent from the following summary of the operation of the valve assembly above described as controlled by the hydraulic circuit shown in FIG. 4.

Initially, the stops 39 and 42 are adjusted as above described and the flow-controlling needle valves 40 and 41 are set to provide the desired flow of trapped fluid from the chamber 22 during acceleration of the plunger. With the valve 21 closed, a supply of fluid under pressure is stored in the accumulator 17 to operate the plunger.

Herein, solenoid-operated pilot valves 96 and 97 are provided to control the operation of the valve actuator. As will be seen from FIG. 4, pilot valve 96 controls the movements of the piston 37 and pilot valve 97 controls the piston 52. When the plunger is at rest, the solenoid 98 is de-energized and the spool 99 of valve 96 is spring-

urged to the left to connect the conduit 49 to a pressure line 100 through check valve 101, while the conduit 47 connects the cylinder 38 to the reservoir through drain lines 102 and 103. The spool 104 of de-energized solenoid 5 107 is urged to the left to connect the head end of cylinder 53 to pressure line 105 and the rod end to drain line 103. Accordingly, both pistons are held in their retracted positions.

To initiate the injection cycle, solenoid 96 is energized and shifts spool 99 to the right as shown in FIG. 4 thereby connecting pressure line 100 to the conduit 47 leading to the rod end of the cylinder 38. At the same time, the chamber 22 is connected to the drain line 103 through the line 48 controlled by the needle valve 40, the parallel line 60 being closed by the pilot valve 97. Thus, the head 21 is moved toward the open position at a rate of travel determined by the setting of the needle 40 until the piston 37 abuts against the rod 54. Preferably, the stop 39 is positioned so that this occurs after the plunger 13 has closed the well 11. Thereafter and until the stop 39 is moved, the plunger advances into the bore at a constant velocity, yielding of the piston 52 being prevented by check valve 106 in pilot pressure line 105.

Means responsive to the position of the plunger preferably is provided to actuate the solenoid 107 for the high speed shot. This means may comprise a switch (not shown) adjustably positioned to trip as the plunger reaches a predetermined point near the end of its stroke. When this happens, the spool 104 is shifted to the right to connect the conduit 34 to the pressure line 105 and admit pressure fluid to the rod end of the cylinder 53 through chamber 82 and conduit 59 thereby urging the piston 52 away from the piston 37 so that the latter is free to move the valve 21 past the selected partially open position. Simultaneously, parallel line 60 is connected to the drain and fluid from chamber 22 may flow past needle 41 as well as needle 40. Thus, the setting of the needle 41 determines the new rate of opening of the valve 21 and the corresponding rate of plunger acceleration. The setting of the stop 42, of course, determines the amount of final opening of the valve 21. In a manner well known in the art, a pressure intensification system (not shown) may be utilized to obtain a final high-pressure compacting of the casting.

45 To withdraw the plunger 13 from the bore 12 and return the pistons 37, 52 to their retracted positions, both solenoids are de-energized and pressure fluid is directed through line 34 to the rod end of the injection cylinder 15. Thus, the machine is in condition for the next injection stroke.

50 It will be apparent from the foregoing that the novel valve assembly provides a unitary control of relatively simple construction and operation and effective to increase the velocity of the plunger in a plurality of precisely controlled steps which are adjustable to produce the wide range of combinations to fit the characteristics of the metal and die being used. The plunger may be accelerated initially at a controlled rate which effects rapid closing of the metal well without danger of splattering molten metal 55 out of the chamber. Then, the constant velocity filling stroke rapidly fills the die cavity with a solid, steady flow of metal. Finally, the high speed shot at the end of the stroke completes rapid filling of the die at a rate which 60 may be selected according to the shape and size of the casting, fluidity and temperature of the metal, and any other pertinent factors. Thus, the valve is adaptable to insure proper control under a wide variety of different 65 circumstances.

We claim as our invention:

70 1. A valve assembly including, in combination, a valve body, a hollow cylindrical sleeve threaded into a recess in said body, a partition dividing said sleeve intermediate its ends into first and second cylinders disposed in end-to-end relation, first and second pistons slidably respectively in said cylinders, a valve movable back and forth in a

passage between an open position and a closed position, said valve being connected to said first piston whereby movement of the latter in one direction shifts said valve toward said open position, a member supported on one of said pistons and journaled in said partition to terminate adjacent the other of said pistons thereby forming a stop for blocking sliding of said first piston when said valve is in a partially open position, means for turning said sleeve into and out of said body to adjust the position of said stop relative to said piston thereby to vary said partially open position, a second member extending through and threaded in one end of said sleeve to terminate adjacent and in the path of said second piston and form a second stop limiting sliding of the second piston away from said first piston and thereby determining said open position, means for turning said second member into and out of said sleeve to vary the position of said second stop relative to said second piston, and means for delivering pressure fluid to said first cylinder to move said first piston against said first stop and thereafter to said second cylinder to move said second piston against said second stop whereby said valve is shifted into said open position.

2. A valve assembly including, in combination, a valve body, a sleeve journaled in said body for axial shifting therein, a partition dividing said sleeve intermediate its ends into first and second cylinders disposed in end-to-end relation, first and second pistons slidably respectively in said cylinders, a valve supported by said body and mov-

able back and forth between an open position and a closed position, said valve being connected to said first piston whereby movement of the latter in one direction shifts said valve toward said open position, a member supported on one of said pistons and extending through said partition to terminate adjacent the other of said pistons thereby forming a stop for blocking sliding of said first piston when said valve is in a partially open position, means for delivering pressure fluid to said first cylinder to move said first piston in said one direction and said valve into said partially open position and thereafter to said second cylinder to move said second piston away from said first piston, a second member supported on said sleeve and disposed in the path of said second piston to form a second stop limiting sliding of the second piston away from said first piston, means adjustably positioning said sleeve axially in said body to vary the position of said first stop relative to said first piston, and means adjustably positioning said second member axially of said sleeve to vary the position of said second stop relative to said second piston.
